1

This invention relates to electrical resolvers. In prior patents I have described machines allowing to effect calculations of different sorts by means of purely electrical devices which, according to the kind of calculations to be made, utilize either linear or sinusoidal potentiometers and various compensation devices enabling the various elements of the resolver to be arranged in series without provoking any reaction of one of these elements on those preceding it.

The present invention is concerned with elements of similar electrical resolvers which however do not carry out simple operations such as additions, subtractions, multiplications and divisions, but obtain by electrical means the geometric sum of several values and in particular the determination of any triangle and generally the resolution of a vector into its components in different directions and the determination of a vector from two components in any directions.

In the drawings affixed to this specification and forming part thereof various embodiments of my invention are illustrated diagrammatically by way of example.

In the drawings,

Figs. 1, 2, 2a and 2b are diagrams illustrating different problems to be solved with the aid of devices according to this invention.

Fig. 3 illustrates a calculating device operated with direct current, with the aid of which the vector AC in Fig. 2 can be calculated, if the length of the vectors AB and BC and the angle enclosed by them are known.

This device allows of solving any triangle, of which two sides and the angle opposed to one of them are known, as illustrated in the diagram of Fig. 2a, or one side and the two adjacent angles are known, according to the diagram of Fig. 2b.

Fig. 4 is a purely schematic showing of the way in which a field of predetermined magnitude can be created in a resolver according to this invention by a transmitting machine, while

Figs. 5 and 6 are diagrams showing by way of example a magnetic and an electronic relay adapted for use in the device here in view.

These electromagnetic devices comprise two identical transmitting machines and a resolver. They have become known mainly by studies I published and are described in detail in the specification of my Patent No. 1,567,941, dated December 29, 1925, for "A Complete Electric Distance Control Apparatus." In the present invention they are combined in a novel manner for the obtainment of certain predetermined results.

2

The device of Fig. 3 comprises two identical machines 33 and 36 which are fed respectively with the voltages U_1 and U_2 , being direct current motors in which the motor field winding 35 and the armature 36 are fed in parallel. They have mounted above the commutator 37 a system 40 of movable brushes arranged at angles of 120° relative to each other and are connected to a receiver machine 42 by means of contact rings. 10 This latter machine 42 resembles a dynamo with two distributed field windings 43 and 44 and an armature carried along at constant speed by a motor 91 and provided with a commutator 90 on which slide two pairs 45 and 46 of brushes (each pair being insulated electrically from the other) which are mounted on a support 49 constituted by two arms extending at right angles to one another.

The brushes 40 of the transmitters are connected to three homologous points spaced 120° , of the inductors 43 and 44. The brushes 46 are connected to the entrance terminals of a magnetic, or preferably an electronic, relay 47 which controls the stopping and the running in one or the other direction of a motor 48 which carries along one of the movable members of the apparatus according to the problem to be solved (resolving of the triangles, Figs. 2, 2a or 2b).

The device 47 serving for starting the motor in one or the other sense has been designated by the general term of "relay." Obviously this device, which is not in itself part of the invention here described and claimed, may, according to the circumstances of each individual case, be of any electromagnetic or electronic type. In the case here in view the use of an electronic relay acting as amplifier offers an important advantage.

In order to assure the greatest precision, it is necessary to be able to ascertain the extremely feeble voltage which would correspond to a very minute displacement and to utilize this voltage for the control of the motor.

An electronic amplifying relay fulfills these conditions by permitting to obtain by a very low voltage to be applied on the entering side (first grid circuit), a voltage at the outgoing side (last plate circuit) sufficing for actuating, directly or indirectly, the commutator controlling the starting, in one or the other sense, of the motor 48.

In Fig. 4 that part of the resolver 42 which represents one of the coils, for instance 44, is illustrated under the form of an inductor 120 with 6 pole pieces arranged pairwise in diametrical opposition and displaced 60° from each other

so that the windings 121—121', 122—122' and 123—123' which embrace the pole pieces, are fed with 3-phase current, whereby a rotating magnetic field is created at 120.

It should be understood that instead of the simple device shown in the drawing, any other system of windings might be used which when fed with 3-phase current, would produce a rotating field.

The transmitting machine 36 is represented in this sketch only by its commutator 37 on which can turn the 3 brushes 40.

As is well known, in a transmitting machine such as here shown (33 and 36) fed with continuous current, the segments of the commutator 37 possess at any time potentials depending on the position the segment occupies in space at that moment and these different potentials are distributed on the commutator 37 in accordance with a mainly sinusoidal law.

Therefore if on this commutator were mounted two brushes in diametrical opposition and were made to turn on the commutator, there would be obtained on these brushes an alternating current the intensity of which would depend on the feed voltage U_2 of the machine while its frequency would depend on the speed of revolution of the brushes.

It is easy to see that if the pair of brushes were replaced by 3 brushes 40 displaced 120° relative to each other, one might collect on them a 3-phase current, the intensity of which would depend on the feed voltage U_2 of the machine, while its frequency would depend on the speed of revolution of the brushes 40 on the commutator.

If one now connected these 3 brushes 40 with the 3 windings, as is shown in Fig. 4, one generates in this resolver a rotating field, the constant intensity of which depends on the feed voltage U_2 of the transmitting machine and which will turn in synchronism with the 3 brushes 40. Such a transmitting machine is described more in detail in my patent mentioned hereinabove.

In the case of the present invention, the 3 brushes 40 do not revolve on the commutator but remain fixed in the position at which they have been set. Under these conditions the field produced in the resolver is not a rotating field any more. It will retain a fixed direction which depends on the relative adjustment of the brushes 40 and its well determined intensity will depend on the feed voltage U_2 . In this manner the transmitting machines 36 will create the flux ϕ_2 , while the machine 33 which feeds the winding 43, will create in the same manner the flux ϕ_1 .

Since the magnitude of the flux ϕ_2 (or field intensity) depends solely on the feed voltage U_2 of the transmitting machine, while its orientation depends solely on the position of the brushes 40, it is clear that if, while leaving the brushes in their position, the voltage U_2 is varied in some way, the field will retain the same direction, but its intensity will vary when the transmitting machine is fed a variable voltage U_2 , one obtains in the resolver a variable flux ϕ_2 of predetermined direction. The flux ϕ resulting from the two variable fluxes ϕ_1 and ϕ_2 will thus be of variable magnitude and fixed as to its direction.

The armature currents can easily be tapped off the armatures 45 and 49 (Fig. 3) by means of brushes gliding on the rings.

As regards the nature of the relay 47, which does not form as such a part of this invention,

two examples are shown in Figs. 5 and 6 for an electromagnetic relay and an electronic relay, respectively. The relays must be reversing, which means that they must change the direction of the current feeding the motor 48. This motor which does not present any special aspect, might obviously be represented by a mere rectangle.

The electromagnetic relay shown in Fig. 5 would be of the polarized type, for which many different forms are known, i. e. of a type in which the armature occupies different positions according to the direction of the current feeding the relay.

In Fig. 5 this relay is represented by a winding 101 connected to the brushes at the end of the arm 46 and by two armatures 102 and 103 which may take up three positions:

1. When the relay is not excited, a position 20 of rest, in which these armatures do not make any contact;

2. When the relay is excited, 2 working positions, at which these armatures are connected to the upper and lower contacts according to 25 the direction of the current passing through the winding 101. This figure shows clearly that the current from the battery 104 which feeds the motor 48, passes through this motor in one or the other direction according to whether the armatures 102 and 103 are in touch with the upper or lower contacts.

Fig. 6 shows, also in a purely diagrammatic manner, an electronic reversing relay which is constituted by two triodes 105 and 106, the grid 35 circuits of which are connected to the brushes 49, however in opposite sense, which means that every brush is connected to the grid of one triode and the cathode of the other triode. If the grids are biased, for instance by the elements 40 107 and do not allow the passage of the electronic current unless the potential of the brush 49 connected to this grid is positive with respect to the potential of the other brush, the electronic current will always pass only through a single 45 one of the triodes at a time and it will not pass through any triode when the brushes have the same potential. If the plate circuits of the triodes are connected, however in opposite direction to the motor, as represented in the figure, it 50 is clear that according to whether it will be one or the other brush 49 which has the highest potential, it will also be one or the other of the triodes 105 and 106, through which an electronic current will pass and that consequently the current passing through the motor will be directed in 55 one or the other sense.

Apart from the general advantages, set out above, offered by the use of an electronic amplifier relay, it also offers another important advantage in the case of the device shown in Fig. 3 which comprises a revolving armature. Such a relay merely requires a voltage to be applied to its entrance side (first grid circuit), while the 60 intensity of the grid current may be considered as altogether negligible. Under these conditions the armature of the resolver does not produce any discharge of current in the outer circuit.

In consequence thereof the machine will not produce any phenomenon of armature reaction which might displace the direction of the resulting flux and, owing to the position, corresponding to zero voltage.

When the transmitting machines are supplied with direct current voltages U_1 and U_2 , each of 75 them obviously produces in one of the field mag-

nets of the resolver a flux ϕ_1 or ϕ_2 , the value of which depends from the values of U_1 and U_2 and from the direction for which the brushes 40 are adjusted on the collectors of their respective machines. These two fluxes result in a flux ϕ_3 which is obtained according to the rule of a parallelogram, as indicated on the drawing.

In order to resolve a triangle of which two sides and the angle between them (AB—BC and β in Fig. 2) are known, one connects the motor 48 mechanically with the rotary support 49. If one then gives to the voltages U_1 and U_2 values proportional to the sides AB and BC of the triangle in Fig. 2, while so adjusting the brushes 40 that the fluxes ϕ_1 and ϕ_2 enclose between them an angle of $180^\circ - \beta$, it can be seen that the triangles having as their sides ϕ_1 and ϕ_2 and ϕ_3 are equal to the triangle ABC of Fig. 2.

If then the system of brushes 45, 46 occupies the position shown in the drawing, i. e. if the line of the brushes 46 coincides with the direction of the resulting flux ϕ_3 , it will be seen that the voltage U_3 between these two brushes is proportional to ϕ_3 and therefore is to be found on the third side AC of the triangle ABC, whose angles γ and δ are indicated by the adjustment of the brushes 40 of the transmitting machines.

On the other hand the two brushes 45 carry the same voltage which has for its consequence that the relay 47 is not excited and therefore the motor 48 remains at rest.

If however the brushes 45, 46 were not in the position shown on the drawing, then the brushes would carry different voltages and the relay 47 would move into one of its operative positions, the motor 48 would start and would carry along the support 49, until the brushes 45, 46 occupied the position shown in the drawing at which the motor 48 would come to a standstill. The value of the voltage U_3 and the adjustment of the brushes would then indicate the elements sought for, viz. AC, γ and δ of the triangle ABC.

The same device allows to resolve the triangles of Figs. 2a and 2b by mechanically coupling the motor 48 with one of the brush systems 40 in the first case and with a potentiometer 92 which regulates U_2 in the second case.

In order to resolve the triangle 2a, in which one knows two sides and the angle opposite one of them, one regulates the voltages U_1 and U_2 in such manner that they become proportional to the two known sides AB and BC of the triangle, one fixes the support 49 in position and so adjusts the position of the brush system 40 of the transmitting machine that the flux ϕ_2 which is produced, encloses with the line of brushes 45 the given angle γ . In that case the motor 48, acting on the brush system of the transmitting machine 33, shifts them into the position in which the brushes 46 carry equal voltages. As in the case above discussed, the final angle at which these brushes are positioned, and the value of the voltage U_3 at the brushes 45 indicate the elements of the triangle ABC looked for.

In order to resolve the triangle 2b, of which one side AB and the adjacent angles β and δ are known, one couples mechanically the motor 48 with a rheostat 92 which enables the voltage U_2 to be adjusted. After having fixed in place the support 49, one so adjusts the system of brushes 40 of the transmitting machines that the fluxes ϕ_1 and ϕ_2 enclose with the line of brushes 46 the angles β and δ whereupon, while leaving U_1 in fixed position, one allows the motor 48 to adjust U_2 by acting on the rheostat 92.

When the motor stops running, it is because the brushes 46 carry the same voltage and, based on the same reasoning as before, the values of U_2 and U_3 are in the same relation with the sides 5 AC and BC as the voltage U_1 with the known side AB.

It should be noted that since the armature is rotated by the motor 91 at a constant number of revolutions (which might be determined), the device 10 acts like an amplifier.

The voltages U_1 and U_2 give rise to excitation current of little intensity, whereas the resulting voltage U_3 is formed by the armature of the machine which is capable of generating a considerable current depending on the dimensions 15 and number of revolutions of the armature, the power derived from the working circuit being provided by the driving motor and not by the calculation circuit which provides the voltages 20 U_1 and U_2 .

Apart from this, it has been assumed in the foregoing description that the driving motor 91 would run at constant speed, but it is possible to adjust or vary the speed as desired by any 25 conventional means such as a resistor 91' connected to the motor 91. In that case the voltage U_3 is proportional to both the flux ϕ_3 and the speed of the driving motor, i. e. to their product, so that by choosing for this speed a value proportional 30 to a predetermined coefficient, the voltage U_3 would be multiplied by this coefficient. The machine could thus be used for obtaining in one operation the geometric sum of two vectors and the multiplication of the result by a predetermined 35 figure.

The foregoing description concerns a certain number of devices of the electromagnetic type which allow of determining the algebraic sum of vectors as well as their resolution according to 40 given directions. The embodiments of this invention disclosed in the specification and in the drawing are merely meant to be examples without in any way limiting the scope of the claims which I intend to cover all variations included by their wording.

45 I claim:

1. An electrical resolver for the solution of triangles, the geometrical addition of vectors, and the resolution of a vector into components thereof, comprising two polyphase stator windings, a rotor winding, a commutator connected to said rotor winding, two polyphase generators exciting, respectively, said stator windings with polyphase voltages producing fluxes in said stator windings, respectively, at predetermined angles, means including an auxiliary motor connected to said commutator for rotating said rotor winding at a constant speed, a first pair of diametrically opposite brushes arranged in contact with said commutator, a second pair of brushes arranged in contact with said commutator 90° apart from said first pair of brushes, a relay connected to said first pair of brushes, voltage taps connected to said second pair of brushes, and electromagnetic means fed by said relay and connected to move said first and second pairs of brushes so as to reduce to zero the potential difference across said first pair of brushes.

2. An electrical resolver for the solution of triangles, the geometrical addition of vectors, and the resolution of a vector into components thereof, comprising two polyphase stator windings, a rotor winding, a commutator connected to said rotor winding, two polyphase generators exciting, respectively, said stator windings with poly-

phase voltages producing fluxes in said stator windings, respectively, at predetermined angles proportional to two sides of the triangle, respectively, means including an auxiliary motor connected to said commutator for rotating said rotor winding at a constant speed, a first pair of diametrically opposite brushes arranged in contact with said commutator, a second pair of brushes arranged in contact with said commutator 90° apart from said first pair of brushes, a relay connected to said first pair of brushes, voltage taps connected to said second pair of brushes, means for connecting said voltage taps to a voltage proportional to the third side of the triangle, and electromagnetic means fed by said relay and connected to move said first and second pairs of brushes so as to reduce to zero the potential difference across said first pair of brushes.

3. An electrical resolver for the solution of triangles, the geometrical addition of vectors, and the resolution of a vector into components thereof, comprising two polyphase stator windings, a rotor winding, a commutator connected to said rotor winding, two polyphase generators exciting, respectively, said stator windings with polyphase voltages producing fluxes in said stator windings, respectively, at predetermined angles proportional to two sides of the triangle, respectively, means including an auxiliary motor connected to said commutator for rotating said rotor winding at a constant speed, a first pair of diametrically opposite brushes arranged in contact with said commutator, a second pair of brushes arranged in contact with said commutator 90° apart from said first pair of brushes, a relay connected to said first pair of brushes, voltage taps connected to said second pair of brushes, means for connecting said voltage taps to a voltage proportional to the third side of the triangle, and electromagnetic means fed by said relay and connected to move said first and second pairs of brushes so as to reduce to zero the potential difference across said first pair of brushes, said ro-

tor winding acting as an amplifier having the output power thereof supplied by said auxiliary motor.

4. An electrical resolver for the solution of triangles, the geometrical addition of vectors, and the resolution of a vector into components thereof, comprising two polyphase stator windings, a rotor winding, a commutator connected to said rotor winding, two polyphase generators exciting, respectively, said stator windings with polyphase voltages producing fluxes in said stator windings, respectively, at predetermined angles, means including an auxiliary motor connected to said commutator for rotating said rotor winding at a constant speed, means for adjusting the speed of said auxiliary motor, a first pair of diametrically opposite brushes arranged in contact with said commutator, a second pair of brushes arranged in contact with said commutator 90° apart from said first pair of brushes, a relay connected to said first pair of brushes, voltage taps connected to said second pair of brushes, and electromagnetic means fed by said relay and connected to move said first and second pairs of brushes so as to reduce to zero the potential difference across said first pair of brushes.
